UNITED STATES PATENT OFFICE.

JOHANN HARMATTA, OF SZEPESVARALJA, AUSTRIA-HUNGARY.

RAIL-FASTENING.

1,080,008.

Specification of Letters Patent.

Patented Dec. 2, 1913.

Application filed October 21, 1912. Serial No. 727,053

To all whom it may concern:

Be it known that I, JOHANN HARMATTA, a subject of the King of Hungary, and resident of Szebesvaralja, Austria-Hungary, 5 have invented certain new and useful Improvements in Rail-Fastenings, of which the following is a specification.

For iron sleepers, the fixing of the rails is of greatest importance. First of all, the 10 sleeper must, if possible, not be perforated and, further, the rail must receive an immovable arrangement. According to the present invention, the rail is, under this consideration, connected with the sleeper by 15 electric welding. Thereby, a faultless connection of the rail with the sleeper is obtained and an exact, proper and permanent mounting of the rail on the sleeper is secured. Changes of the width of the track 20 or of the inclination of the rails in curves are impossible, while, further, the rail is prevented from creeping and, finally, a most reliable transmission of pressure on the sleeper is secured. Of greatest importance 25 is further the easy and quick way of fixing the rail on the sleeper, and the impossibility of loosening this connection without complicated auxiliary means, so that accidents, which hitherto happened owing to criminal 30 disconnection of rail and sleeper, are now practically impossible.

The fixing of the rail on the sleeper by 35 electric welding may be effected either directly or through the medium of a correspondingly wedge-shaped tie-plate. As the rail forms then with the latter and the 40 sleeper a homogenous body, any loosening is impossible. The disconnection is only possible in a mechanical or thermic way, the welded sections being in the former case

sawed or bored asunder or, while in the latter case they must again be brought on welding heat in order to be separated.

The accompanying drawing shows the improved arrangement.

Figure 1 is a cross section, and Fig. 2 a plan view, of the improved rail-fastening.

The sleeper *a* is, according to the invention, connected with the rail *b* through the medium of a correspondingly wedge-shaped 50 tie-plate *c* in such a way that single points *e* which touch each other, are electrically welded. This may be effected by holding electrodes *d* of a stationary or movable power source on said points until the latter 55 are brought on welding heat whereupon they may be at once connected by a slight pressure only. The rail-fastening, as above described, can thus be effected in a very easy and safe way and need no later attendance, 60 while it insures the greatest security and rigidity of the connection. The sleeper itself may further be provided with ribs, or with a single rib or projection, which serves as a strengthening for the same. The welding 65 may be effected on any size of surface, which can therefore be larger than the stronger section of the parts to be welded.

I claim:

A rail-fastening consisting of a sleeper 70 and an intermediary tie-plate, the latter being welded together and the tie-plate to the rail in an electric way.

In testimony whereof I have hereunto set my hand in the presence of two subscribing 75 witnesses.

JOHANN HARMATTA.
